UNITED STATES PATENT OFFICE.

ARCHER W. DOUGLAS, OF ST. LOUIS, MISSOURI, ASSIGNOR TO SIMMONS
HARDWARE COMPANY, OF ST. LOUIS, MISSOURI, A CORPORATION.

DESIGN FOR A PADLOCK.

No. 37,771.

Specification for Design.

Patented Jan. 2, 1906.

Application filed November 25, 1905. Serial No. 289,136. Term of patent 14 years.

To all whom it may concern:

Be it known that I, ARCHER W. DOUGLAS, a citizen of the United States, residing in the city of St. Louis and State of Missouri, have invented a new, original, and ornamental Design for Padlocks, of which the following is a specification, reference being had to the accompanying drawing, forming part thereof.

The figure is a perspective view of a padlock showing my new design.

I claim—

The ornamental design for a padlock, as shown.

ARCHER W. DOUGLAS.

In presence of—

J. E. SMITH,
F. W. ALLEN.
